DOOR CONSTRUCTION

Filed June 20, 1928 2 Sheets-Sheet 2

UNITED STATES PATENT OFFICE

FREDERICK WILLIAM CUFFE, OF WAYNESBORO, VIRGINIA, ASSIGNEE, BY MESNE ASSIGNMENTS, TO EDISON GENERAL ELECTRIC APPLIANCE COMPANY, INC., OF CHICAGO, ILLINOIS, A CORPORATION OF NEW YORK

DOOR CONSTRUCTION

Application filed June 20, 1928. Serial No. 286,893.

This invention relates to a spring and door construction and to be used more particularly in connection with oven doors.

The principle object is to provide a spring 5 of the leaf type, which when connected up with an arm not only serves the usual functions of a spring, but acts as a counter balance to the weight of the door.

Another object is to construct a door 10 frame to which is integrally connected an arm so that the strain and stress of opening the door will be carried by the frame and the enameled surface and back piece which are formed separately are relieved of this 15 strain, thereby saving the enameled surface. In this construction of a door to be used in connection with an oven, there are certain problems which must be taken into consideration. It is highly desirable that a close 20 contact be made at all times while the door is in closed position and further, to present a construction which will as far as possible, prevent the warping and sagging of the door frame. Further, where an enameled outer 25 surface is used, it is highly desirable to relieve the same of any strain as enamel has a tendency to crack and chip off when its base is warped, twisted or subjected to strain.

Still another object is to provide an adjustable feature in connection with tensioning a spring wherein greater or less counter balancing effect may be obtained. The door spring serves more as a counter balance than a spring as upon the door being released, the weight of the door will cause the same to gradually sink until a horizontal position is reached. By using the spring as a counter balance to the weight of the door, and having a plurality of springs, there is no chance for the sudden dropping of the door which often results in the chipping off of the enamel and straining of the frame. The door thus connected is very easily manipulated so that when it is desired to close the door only a very slight effort need be exerted.

Other objects will be disclosed in the specification and drawings.

In the drawings

Figure 1 is a front elevation showing the door in place;

Figure 2 is a section taken along line 2—2 55 of Figure 1, showing a spring and arm attached to the door frame;

Figure 3 is a bottom plan showing the springs in position;

Figure 4 is a fragmentary section corresponding to Figure 2 showing the oven door 60 in open horizontal position;

Figure 5 is a side elevation partly in section showing the method of mounting the door;

Figure 6 is an inside elevation with one cover broken away to show the frame construction of the oven door;

Figure 7 is a top view of the door with parts broken away;

Figure 8 is a perspective of the oven door frame removed to show its construction; and

Figure 9 is a section taken on line 9—9 of Figure 6.

Referring to the drawings

Numeral 1 designates an oven door consisting of an enameled cover plate 2, a back plate 3, and a frame 4 enclosed within the back and front members 2 and 3. In order 80 to get the greatest rigidity, the frame 4 is formed of U-shaped side members 5, rivetedly connected to a cross member 6 at the top and secured at the bottom to a cross bar 7 by way of a triangular brace plate 8 which 85 carries as an integral part thereof arms 9. By having the side members 5 formed of U-shaped members, and the bottom cross member closely adjacent and both secured in place by the brace plate 8 which forms an 90 integral part of the arm 9, very rigid construction is obtained. By mounting the hinges 10 on the brace plate 8, all strain is removed from the front and rear plates altogether. The arm 9 has a stop member 11 95 in the form of a shoulder which limits the downward movement of the frame 4. The arm 9 is adjustably connected to a curved leaf spring 12 by a hook 13 which is shown adjustably secured at 13' by a wing nut 14. 100

The leaf spring 12 is secured to a supporting structure 15 at 16 with substantially the entire curve occurring at this secured end, and within a compartment formed by a partition 17 having an opening 18 to allow easy removal of the spring and at the same time prevent an upward movement. Attached to the bottom of the brace plate 8 are hinges 10 which may be inserted through openings 19 in supporting structure 15 and secured in place by means of screws 20.

The back plate 3 which has a flange 21 and a receding back wall 22 is thus made in order to provide as perfect and tight a fit 15 as possible upon the oven door being closed.

At the top of the oven door, carried by the top cross member 6 is a combined handle and locking means 23. This member has a handle 24, and is pivoted at 25 so that when a downward pressure is exerted on the handle 24, the opposite end 26 is forced into a metal clip 27, thus forcing the inner face of the door against the oven 28. By securing the combined handle and locking means to the 25 cross member 6, the strain which results from forcing the oven door against the face of the oven 28 is borne by the frame 4 and not by the outside cover 2, thus preventing the resulting loss of enamel.

As actually used, the door frame 4 with the arms 9 would be first constructed and the back and front plates 3 and 2, respectively, secured to the frame 4, the arms 9 would then be connected up to the two flat springs 35 12. The oven door as a whole would then be raised slightly and opened approximately ten degrees. The hinges 10 would then be inserted in the openings 19 and the whole secured in place by means of screws 20.

By pulling up on handle 24, the door 1 is free to swing down and because of the counter balance effect of springs 12, there is no danger of a sudden jolt or jar due to the sudden dropping of the door. Ordinarily 45 the tension of the spring and weight of the door is such that the door will normally seek a horizontal position, but due to the fact that dishes are often placed on the open door, a stop 11 in the form of a shoulder will prevent the door from being forced below the horizontal position.

When it is desired to raise the door, because of the near balance of the weight of the door and the counter balance effect of the 55 springs, the door will with very little effort on the part of the operator be restored to a closed position. The operator by lifting up on the handle 24 and pushing inwardly on the door and then pushing down on handle 24 60 when end 26 is beneath the spring clip 27, will force the inner surface of door 1 snugly against the face of the oven, and thus procure a very snug fit which prevents the escape of heat from the oven.

By having the back and front pieces 3

and 2, respectively, formed separately from the door frame 4 all strain is removed from these two portions and there is less chance of sagging and warping, with the chances of chipping of the enamel on the front piece 2 reduced to a minimum. The usual packing 70 29 is placed between the front and back pieces around the frame member, the front piece 2 overlaps the back piece 3, and the two are secured together by screws 30. These screws do not pass into the frame 4, but merely serve to hold the front and back pieces 2 and 3 together.

The back piece 3 is secured to the U-shaped side members 5 by means of screws 31. The back plate 3 can be so secured as it has no enamel on its outer surface. The front plate 2, which is covered with enamel, must be relieved of all strain as far as possible, so it is secured at the top by the handle and locking means 23, which is secured to the frame 4 by screws 32.

The front piece 2 merely overlaps the back piece 3, and is secured at the sides and bottom by the screws 30. The hinges 10 are secured to the bottom of brace plate 8 and extend through openings 33 formed in the edges of the front and back plates 2 and 3, respectively, the hinges 10 being free of these plates. From this it is apparent that there will be little or no strain on the front enamel plate 2 and yet a rigid and strong construction is provided.

By the use of two springs, the chances for positive action are greatly increased as even if one should become broken or out of order the other would still continue to function. By using a spring of the type disclosed, greater length is obtained thereby reducing the flexure per inch of length to a minimum. This of course results in a minimum unit stress with a resulting long life. Further, it is highly desirable to prevent undue heating of the springs and by having them removed and open to circulation, same cannot become overheated which sometimes results in a partial annealing as well as loss of temper.

What I claim is:—

1. A door construction comprising a supporting structure, a frame, pivot means connecting the frame to said structure, an arm secured at an angle to said frame, a leaf spring having one end secured to said structure, and having its other end connected to said arm, said spring acting as a yielding counterbalance to said frame.

2. A door construction comprising a supporting structure, a frame pivotally connected to said structure, an arm secured at an angle to said frame, a leaf spring secured to said structure, means for adjustably connecting said leaf spring to said arm, said arm and spring acting as a yielding counterbalance to said frame.

3. An oven door construction, comprising a

frame, a pair of plates covering opposite faces of said frame, said frame comprising a unitary supporting structure independent of said plates and having one of said plates secured directly to said frame, a handle detachably connected to said frame and clamping the unsecured plate to said frame.

4. An oven door construction, comprising a rectangular frame, a pair of plates covering opposite faces of said plates and having overlapping edges, said frame comprising a unitary supporting structure independent of said plates and having one of said plates secured directly to said frame, means for detachably connecting one of the overlapping edges of one plate to the other plate, and a handle detachably connected to said frame and clamping the unsecured plate to said frame.

5. A door construction comprising a supporting structure, a unitary frame pivotally connected to said structure, front and back pieces detachably secured to said frame, said frame comprising a supporting structure independent of said pieces, means secured to said frame for counterbalancing the weight of said frame and pieces on said structure.

6. A door construction comprising a frame, a pair of brace plates, each brace plate securing one side of said frame to an adjacent end member and an arm extending from each of said brace plates parallel to each other and on one side of said frame.

7. A door construction comprising a frame, a pair of brace plates, each brace plate securing one side of said frame to an adjacent end member, a stop arm extending from each of said brace plates parallel to each other and on one side of said frame.

8. A door construction comprising a rectangular frame having a pair of brace plates, each brace plate securing one side of said frame to an adjacent end member and a stop arm extending from each of said brace plates parallel to each other and on one side of said frame, and a pair of hinges secured to said plates.

In testimony whereof I affix my signature.
FREDERICK WILLIAM CUFFE.
